UNITED STATES PATENT OFFICE.

W. EDMANDS BABBITT, OF PORTSMOUTH, NEW HAMPSHIRE, ASSIGNOR OF TWO-FIFTHS
TO RALPH W. FOSTER, OF BOSTON, MASSACHUSETTS.

RESILIENT WHEEL.

1,392,262.

Specification of Letters Patent. Patented Sept. 27, 1921.

Application filed January 7, 1919. Serial No. 269,998.

To all whom it may concern:

Be it known that I, W. EDMANDS BABBITT, a citizen of the United States, residing at Portsmouth, in the county of Rockingham 5 and State of New Hampshire, have invented in certain new and useful Improvements in Resilient Wheels, of which the following is a specification.

This invention relates to cushioned wheels for vehicles and its object is to provide a wheel with cushioning means so constructed and disposed that while most effective and reliable this means shall be protected from punctures and other injuries.

15 The invention is illustrated by the accompanying drawings in which:

Figure 1 is a side elevation of the wheel with portions of the tube cut away and without the rim; and

20 Fig. 2 is a central horizontal section on line 2—2 Fig. 1.

As illustrated, the wheel comprises three concentric disks: the outer disk 1; the middle disk 2, to which the rim of the wheel (not shown) is attached; and the inner disk 3; the middle disk being confined between the outer and inner disks in sliding engagement therewith.

The outer disk 1 is furnished with the 30 extended tubular hub 1^a adapted to engage rotatably or fixedly the axle 4; said disk 1 being furnished also with a peripheral wall consisting of equally spaced sections 1^b projected perpendicularly therefrom.

35 The middle disk 2 has a central opening 2^a and a series of equally spaced peripheral openings 2^b for the passage therethrough respectively of the hub 1^a and sections 1^b of the wall of the outer disk 1.

40 The inner disk 3 is furnished with the tubular hub 3^a and with the peripheral wall 3^b projected perpendicularly therefrom and fits tightly within the walls of disk 1, being held in place by the ring 1^c fixed on the tubular hub 1^a; said inner disk 3 being furnished 45 also with a series of openings 3^c for the purpose hereinafter explained.

The spiral wall 5 rises perpendicularly from a plane parallel to and just above that 50 of the inner face of the inner disk 3, so as to clear said disk, and is affixed to middle disk 2 by feet or lugs 5^a which extend through the openings 3^c in disk 3.

When the parts above described are assembled, the outer disk 1 and the inner disk

3 constitute a single disk, apertured, slotted and walled as described, and confining between them in sliding engagement therewith the middle disk 2.

The spiral wall 5 is of such length and so 60 plotted and attached to the middle disk 2 that its inner and outer end portions are preferably left free, and it forms with the tubular hub 3^a and the peripheral wall 3^b of the inner disk 3 a continuous walled spiral 65 chamber 6 for the reception and confinement therein of the pneumatic tube 7, which forms a cushioned support both for the hub 3^a (and axle 4) and also for the peripheral wall 3^b of disk 3, or in other words for the 70 hub and the upper half of the wheel when attached to a vehicle or in an approximately vertical position.

It is obvious from the above description of the invention that, when the wheel is 75 traveling either forward or backward, the outer disk 1 and inner disk 3, constituting, as has been said, practically one suspended disk, will have at times a tendency to travel either a little faster or a little slower than 80 disk 2 which is connected through the rim of the wheel (not shown) with the ground; and to prevent such difference in speed of these portions of the wheel, resulting at 85 times in much annoyance, I attach to the inner and outer ends of the tube 7 a piece of fabric 8 which being engaged by the corresponding ends of the spiral wall 5 prevents any appreciable sliding movement of 90 the tube on the spiral wall; and for the same 95 purpose I furnish the inner surface of the wall 3^b of disk 3 with lugs or projections 9 which sink into the tube 7 and prevent any appreciable sliding movement of the tube on the wall 3^b; and for the same purpose I 100 furnish the tube with lugs or projections 10 which engage corresponding recesses 11 in the wall 3^b; and I provide against the shock incident to any contact of the feet 5^a with the walls of the openings 3^c by furnishing the feet with a sleeve 12 of resilient material. Lugs 13 on the tube 7 serve to cover the openings 3^c. A valve for inflating the tube is indicated at 14.

The combined dust shield and chamber 105 cover 15 may be fastened to the walls of the chamber or it may be extended beyond these walls and carried downwardly and affixed to the middle disk 2.

If so desired, the inner and outer portions 110

of the spiral wall 5 may be hinged, as at 16, to make those portions more yielding, or they may be omitted, thus permitting the tube 1 at its inner and outer ends to overlie 5 itself.

The spiral wall is preferably made of spring steel.

The tube may be made of any resilient material and an inner tube (not shown) may 10 also be employed.

The details as to many matters described and illustrated may be varied as desired; for example, the spiral wall 5 may be furnished with lugs or projections 9 and recesses 11 for the purpose stated; and other methods than those shown may be employed for interlocking the tube and chamber walls.

The word "Spiral" is herein employed broadly to include any expandable and contractible chamber winding upon itself.

I claim:

1. A resilient wheel comprising two concentric disks of different diameters slidable one on the other; the hub-disk of lesser diameter and furnished centrally with a hub and peripherally with a wall; and the rim-disk of greater diameter, annular and furnished with a spiral wall disposed between

the hub and the peripheral wall of the hub-disk and forming therewith a spiral chamber. 30

2. A resilient wheel comprising two concentric disks of different diameters slidable one on the other: the hub-disk of lesser diameter and furnished centrally with a hub and peripherally with a wall; and the rim-disk of greater diameter, annular and furnished with a spiral wall disposed between the hub and the peripheral wall of the hub-disk and forming therewith a spiral chamber. 35

3. A resilient wheel comprising two concentric disks of different diameters slidable one on the other and furnished with walls so disposed as to form an expandable and contractible spiral chamber. 40

4. A resilient wheel comprising two concentric disks of different diameters slidable one on the other and furnished with walls so disposed as to form an expandable and contractible spiral chamber; and a pneumatic tube disposed in said chamber. 50

In testimony whereof I have affixed my signature.

W. EDMANDS BABBITT.
